Des. 235,687
Patented July 1, 1975

235,687

SURGICAL MASK

Marion Bragg, Palatine, Ill., assignor to The Kendall Company, Walpole, Mass.

Continuation-in-part of abandoned design application Ser. No. 453,776, Mar. 22, 1974. This application Aug. 29, 1974, Ser. No. 499,380

Term of patent 14 years

Int. Cl. D24—02, 99

U.S. Cl. D83—1 K

FIG. 1 is a front plan view of one embodiment of a surgical mask embodying my new design;

FIG. 2 is a fragmentary front plan view of the surgical mask of FIG. 1 on an enlarged scale;

FIG. 3 is a fragmentary rear plan view of the surgical mask of FIG. 1 on an enlarged scale;

FIG. 4 is a sectional view on an enlarged scale taken substantially as indicated along the line 4-4 of FIG. 2;

FIG. 5 is front plan view of a second modified embodiment of a surgical mask embodying my new design;

FIG. 6 is a fragmentary front plan view of the surgical mask of FIG. 5 on an enlarged scale;

FIG. 7 is a fragmentary rear plan view of the surgical mask of FIG. 5 on an enlarged scale;

FIG. 8 is a sectional view on an enlarged scale taken substantially as indicated along the line 8-8 of FIG. 6.

FIG. 9 is front plan view of a third modified embodiment of a surgical mask embodying my new design;

FIG. 10 is a fragmentary front plan view of the surgical mask of FIG. 9 on an enlarged scale;

FIG. 11 is a fragmentary rear plan view of the surgical mask of FIG. 9 on an enlarged scale;

FIG. 12 is a sectional view on an enlarged scale taken substantially as indicated along the line 12-12 of FIG. 10;

FIG. 13 is a front plan view of a fourth modified embodiment of a surgical mask embodying my new design;

FIG. 14 is a fragmentary front plan view of the surgical mask of FIG. 13 on an enlarged scale;

FIG. 15 is a fragmentary rear plan view of the surgical mask of FIG. 13 on an enlarged scale; and

FIG. 16 is a sectional view on an enlarged scale taken substantially as indicated along the line 16-16 of FIG. 14.

This is continuation-in-part of design application Ser. No. 453,776, filed Mar. 22, 1974, and now abandoned.

I claim:

The ornamental design for a surgical mask, substantially as shown and described.
